TIME LAG FUSE

Lambert Schmidt and George Schmidt,
Leeds, N. Y.

Application December 4, 1941, Serial No. 421,552

13 Claims. (Cl. 200—131)

This invention relates to improvements in fuses of the plug and cartridge type and more particularly to improvements in fuses of the above type known generally to the art as time lag fuses.

An object of the present invention is to provide fuses as defined above by simplified construction wherein means are provided for imparting a delay or time lag to the destruction of the fuse element upon a predetermined overload.

Another object of the invention is to provide a fuse of the foregoing character in which the fuse element is held in intimate contact with a heat absorption member, which absorption member is so selected as to retard the fuse action of the fuse strip a predetermined time interval after the initiation of a predetermined overload.

Another object of the invention is to provide a heat absorption member of insulating material and of such size and characteristics relative to a fuse strip as to delay the fuse action of the strip a predetermined time interval upon a designated overload.

A further object of the invention is to provide a fuse so constructed that the fuse element is held in contact with a heat absorption member having a different coefficient of expansion than that of the fuse element whereby continued overload will, after an interval of time, cause expansion of the fuse element out of contact with the heat absorption member over a part of its length so that such element can rupture due to the excess heat therein.

In carrying out the foregoing and other objects of the invention, a time lag fuse embodying the same can be incorporated either in a fuse plug or in a cartridge type fuse. When embodied in a fuse plug, such plug is preferably made up of a base member of insulating material, a hollow top member likewise of suitable insulating material, a fuse element within the plug and a metallic shell securing the parts together. In addition to these members, use is made of a heat absorption member of suitable insulating material against which the fuse element is placed in intimate contact therewith so that this heat absorption member can act to absorb heat generated in the fuse element due to an overload of current therethrough. This heat absorption member is of predetermined size and composition relative to the fuse element or strip so that the element and the strip have widely different coefficients of expansion. Since the heat absorption member is of predetermined size relative to the amperage capacity of the

fuse strip, it follows that this member can absorb heat from the strip until the strip and the member attain approximately the same temperature after which the strip will expand relative to the member and thereafter become so overheated as to rupture. In a cartridge type of fuse embodying the invention, the fuse strip is mounted on an elongated strip of heat absorption insulating material, which absorption member is substantially semi-circular in cross-section and preferably with a groove or channel in the flat top surface thereof. This channel can slope downwardly in each direction from the mid-point to permit a better intimate contact between the fuse strip and the bottom of the channel. If desired, units composed of fuse strips and heat absorption members can be made by fastening fuse strips to such members in more or less permanent condition so that elements 20 can be replaced in a cartridge type fuse by simple insertion of a preformed unit therein.

Other features, objects and advantages of the invention will become apparent by reference to the following detailed description of the accompanying drawing wherein

Fig. 1 is a vertical section through a fuse plug embodying the invention;

Fig. 2 is a perspective view of some of the elements of the fuse plug construction, such elements comprising the base, the fuse strip and the heat absorption member;

Fig. 3 is a central longitudinal section through a cartridge type fuse embodying the invention;

Fig. 4 is a section taken substantially on the line 4—4 of Fig. 3, and

Fig. 5 is a plan view of a replaceable unit embodying the invention and adapted to be introduced into a renewable cartridge type fuse.

Referring now to the drawing and particularly to Figs. 1 and 2, 10 indicates generally a fuse plug of more or less conventional character and embodying the present invention. This plug is made up of a base member 11 of some suitable insulating material and a top member 12 likewise of suitable insulating material, such as for example, glass. The base member 10 has a through aperture in the bottom thereof for the reception of a terminal member 14 having a hollow neck 15 extending into the aperture.

One end of a fuse strip element 16 is secured in the neck part 15 of the terminal 14 by a metallic spring retaining member 17 in the manner set forth in the Patent of Lambert Schmidt, 2,276,703, dated March 17, 1942. This fuse strip 16 extends upwardly from the throat 15 through

a notch in the bottom side wall of a heat absorption member 18, the bottom of which extends into the base member and which has a flange resting on the top of the base 11. The fuse strip also passes under this flange. Member 18 can be secured in place by friction or any other suitable manner. The strip 16 extends across the top of this member 18, which top is slightly rounded as shown, down the other side thereof under the lower edge of the upper housing member 12 and upwardly along the side thereof, preferably in a groove formed in external thread formations on the periphery of the member 12. This outer upwardly extending part of the strip as well as the component parts of the assembly are locked in place by a metallic shell 19 having a flange 20 underlying the base 11 and having its side wall rolled into threads to engage the thread formations on the periphery of the member 12. The fuse strip 16 has a narrowed zone 21 so located as to lie substantially midway across the top of the heat absorption member 18. The top part of member 18 can be shaped as shown for convenience in predetermining the mass thereof.

The heat absorption member 18 is made of some suitable insulating material which is not affected by heat, such as an asbestos compound, or a cold moulded compound, or suitable ceramic material. The fuse strip 16 is adapted to be held or strapped into intimate contact with the member 18 for the purpose to be explained later. The size and material of the member 18 are determined in relation to the amperage capacity of the fuse strip 16 to secure the proper interval of time lag upon a predetermined percentage of overload passing through the strip. For a given amperage capacity fuse strip, the member 18 must be of such size and of such heat absorbing properties that it can absorb heat from the strip for a predetermined length of time before the strip is ruptured at its narrow zone 21. Since the member 18 is made of any of the materials specified and since the strip 21 is made of the usual fuse metal such as some suitable zinc composition, it follows that these parts have different coefficients of expansion with that of the member 18 considerably lower than that of the strip 16.

The operation of this device is substantially as follows. Upon the existence of an overload through the strip 16, such overload causes the strip to become heated but the heat is absorbed from the strip as it is generated, such absorption being accomplished by the member 18. Depending on the mass of this member 18 and its heat absorption properties, the absorption of heat from the strip will continue for a predetermined length of time or until the member 18 reaches a temperature close to that of the strip 16. When such condition exists, which will occur if the overload is sufficient, continued heating of the strip 16 will cause expansion thereof relative to the member 18 since these parts have different coefficients of expansion. The expansion of the strip 16 is limited to that portion thereof extending across the top of the member 18 since the portions of the strip extending along the sides of member 18 are held against expansion by the close fit between the strip, the member 18 and the inner wall of the top part 12 of the casing. Consequently, the expansion of the strip 16 is confined to this zone across the top of the member 18 with the result that this part of the strip lifts out of contact with the top of mem-

ber 18. When such separation occurs, it is evident that the separated part of the strip immediately acquires a high temperature due to the overload with the result that the strip fails at its narrow zone 21 in the manner customary with fuse strips of conventional character. The failure at this point causes the creation of the usual arc but such arc is of relatively short length, and explosion, usually attendant upon rupture of a fuse strip, is eliminated due to the fact that one side of the strip rests on the heat absorption member and is cooled off progressively away from the weak point. As before pointed out, the mass of the heat absorption member can be determined accurately relative to the amperage capacity of the fuse strip to obtain the desired time lag in operation of the fuse for a given overload. By actual tests, it has been proved that if the mass of the heat absorption member is too small the fuse strip is ruptured before the proper time lag has occurred, while if the mass of the heat absorption member is too large, rupture will not occur under the given overload as too much heat is conducted away from the strip for the proper operation thereof.

As for example, the mass of the heat absorption member may be accurately determined so that with a definite overload of the order of say 35%, the time lag in the operation of the fuse strip can be made to attain a period of 45 minutes or any other interval that may be desired. These figures are given for illustrative purposes only. Under the same conditions a smaller overload will naturally extend the period of time lag while this time lag period shortens progressively as the period of overload increases, bearing in mind, however, that with a short in the circuit including the fuse element, the operation of this fuse element in breaking down is substantially instantaneous, since the heat generated in the strip due to the short is so intense that the heat absorption member cannot cool the strip enough to prevent the desired rapid action.

In the arrangement shown in Figs. 3 to 5 inclusive, the invention has been embodied in a fuse of the cartridge type, which device comprises a generally tubular casing 43 made of some suitable insulating material such as fiber or the like. Secured to one end of the casing 43 is an externally threaded member 41, the end of which is partially closed by an integral flat 42 having a small opening 44 adjacent one edge of the member 41. This flat 42 extends across the end of the member 41 to close more than half of such end leaving an opening 45 for the passage of one end of a fuse strip in a manner to be described later. A second externally threaded member 46 is secured to the other end of the tubular member 43 but such second member 46 is substantially open with the exception of a notch 47 at one point along its edge. In conjunction with this end of the assembly, use is made of a partial disc member 48 having a detent 49 to engage the notch 47. Removable terminal cap members 50 and 51 are internally threaded to be attached to the respective members 41 and 46.

In this type of fuse, units embodying the invention can be utilized and each of such units comprises a heat absorption member 55 of material similar to the member 18. The member 55 as shown in the drawing is an elongated member of substantially semi-circular shape in cross-section with a groove or channel in the flat top surface thereof, the bottom of which

channel slopes downwardly in each direction from the mid-point. Positioned in the channel is a fuse strip element 56 having a narrow zone 57 at its mid-point. This strip 56 can be fastened to the heat absorption member 55 by two clip members 58 near each end of the member 55, such clip members overlying the strip and partially passing around the outer surface of the member 55.

Units of this character may be made in pre-assembly as shown in Fig. 5 and inserted into the cartridge fuse casing as they may be desired, it being understood that this type of device constitutes a renewable cartridge fuse. The insertion can be accomplished in the manner customary with fuses of this type by removing the terminals 50 and 51, removing the partial disc 48 and introducing a unit into the housing 40 through the open end surrounded by member 46. One end of the fuse strip 56 is then passed through the opening 45 and bent around the outer end surface of the partial closure 42. This end can then be clamped in place by the terminal cap 50. The other end of the fuse strip 56 can be bent around the outer end of the partial disc 48 which has been placed in position partially closing the end of the member 46 and this second end of the fuse strip locked in place by the terminal cap 51.

The operation of this embodiment of the invention is similar in all respects with that explained hereinbefore in connection with the Fig. 1 embodiment of the invention since the heat absorption member can be of predetermined character to perform the functions described previously in connection with the strip 56, bearing in mind the amperage capacity of the strip and the desired time lag for a definite overheat. The clips 58 aid in localizing expansion of the strip 56 to that portion of the strip between the clips.

From the foregoing it will be seen that the present invention provides a new type of time lag fuse in which all moving parts have been eliminated and which possesses the advantage of utmost simplicity. As before pointed out, any desired time lag with a given overload can be obtained in either of the illustrated devices by properly determining the mass of the heat absorption member relative to the amperage capacity of the fuse strip, the heat absorption characteristics of such member, and its coefficient of expansion relative to that of the fuse strip. All of these characteristics can readily be determined to adapt the device for any desired operating ranges.

It is to be understood that the invention can be modified beyond the illustrated embodiments and consequently any limitations imposed thereupon are to be only those set forth in the following claims.

What is claimed is:

1. In a time lag fuse, a casing, a member of insulating material within said casing, and a fuse strip initially held in intimate contact with the surface of said member, said member being of heat absorption material and of such mass relative to the amperage capacity of said strip as to absorb heat from said strip for a predetermined length of time upon a given overload through said strip, and said strip having a greater coefficient of thermal expansion than said member and having a zone of reduced cross section adapted to move out of contact with said member upon continued overload heating of the strip.

2. In a time lag fuse, a casing, a substantially stationary member of insulating material within said casing, a fuse strip initially held in intimate contact with the surface of said member, said member being of heat absorption material and of such mass relative to the amperage capacity of said strip as to absorb heat from said strip for a predetermined length of time upon a given overload through said strip, said strip being so held in said casing that expansion of the strip is localized, in a portion thereof, and said strip having a greater coefficient of thermal expansion than said member whereby said portion of the strip is adapted to move out of contact with said member upon continued overload heating of the strip.
3. In a time lag fuse, a housing, a member of insulating material within said housing, a fuse strip initially held in intimate surface contact with said member, said member being of heat absorption material to absorb heat from said strip, said member and said strip having different coefficients of expansion whereby separation of the strip from the member occurs upon continued overload heating of the strip and member.
4. In a time lag fuse, a housing, a member of insulating material within said housing, a fuse strip initially held in intimate surface contact with said member, said member being of heat absorption material to absorb heat from said strip, said member and said strip having different coefficients of expansion whereby separation of the strip from the member occurs upon continued overload heating of the strip and member, the zone of such separation being limited to that part of the strip passing over the top of said member.
5. A time lag fuse plug comprising a casing made up of a base, a hollow upper member and a shell holding said parts together, a member of insulating material secured on said base, said member having a rounded top, a fuse strip secured in said casing and having a portion initially in intimate surface contact with said rounded top, said member being of heat absorption material of such mass as to absorb heat from said strip and prevent expansion thereof for a predetermined period upon a given overload through said strip, and said strip having a greater coefficient of thermal expansion than said member whereby a portion of the strip moves out of contact with said rounded top upon continued overload heating of the strip.
6. A time lag fuse plug comprising a casing made up of a base, a hollow upper member and a shell holding said parts together, a member of insulating material secured on said base, a fuse strip secured in said casing and passing over said member initially in intimate surface contact therewith, said member being of heat absorption material of such mass as to absorb heat from said strip and prevent expansion thereof for a predetermined period upon a given overload through said strip, and said strip having a greater coefficient of thermal expansion than said member whereby a portion of the strip moves out of contact with the top of said member upon continued overload heating of the strip.
7. A time lag fuse plug comprising a casing made up of a base, a hollow upper member and a shell holding said parts together, a member of insulating material secured on said base, a fuse strip secured in said casing and passing over said member initially in intimate surface contact therewith, said member being of heat absorption

material of such mass as to absorb heat from said strip and prevent expansion thereof for a predetermined period upon a given overload through said strip, expansion of said strip being limited to that part overlying the top of said member, and said strip having a greater coefficient of thermal expansion than said member whereby a portion of the strip moves out of contact with the top of said member upon continued overload heating of the strip.

8. A time lag fuse comprising a substantially tubular casing, an elongated member within said casing, and a fuse strip initially held in intimate surface contact with said elongated member, said member being of heat absorption material to absorb heat from such strip for a predetermined length of time upon a given overload through said strip, and said strip and member having different coefficients of thermal expansion whereby contact between a portion of the strip and member is removed upon continued overload heating of the strip and member.

9. A time lag fuse comprising a substantially tubular casing, an elongated member within said casing, and a fuse strip initially held in intimate surface contact with said elongated member, said member being of heat absorption material to absorb heat from such strip for a predetermined length of time upon a given overload through said strip, said strip and said member having different coefficients of expansion whereby contact between said strip and a part of said member is removed upon continued overload heating of the strip and member.

10. A replacement unit for cartridge type time lag fuses comprising an elongated member of insulating material; a fuse strip positioned on a surface of said member, and means for retaining said strip initially in intimate surface contact with the member, said member being made of heat absorption material of predetermined mass relative to the amperage capacity of said strip, and said strip and member having different coefficients of thermal expansion whereby contact between a portion of the strip and member is removed upon continued overload heating of the strip and member.

11. A replacement unit for cartridge type time lag fuses comprising an elongated substantially

semicylindrical member of insulating material, said member having a groove in the flat surface thereof, a fuse strip positioned in said groove and means for retaining said strip initially in intimate surface contact with the bottom of said groove, said member being made of heat absorption material of predetermined mass relative to the amperage capacity of said strip, and said strip and member having different coefficients of thermal expansion whereby contact between a portion of the strip and the bottom of the groove is removed upon continued overload heating of the strip and member.

12. A replacement unit for cartridge type time lag fuses comprising an elongated substantially semicylindrical member of insulating material, said member having a groove in the flat surface thereof, the bottom of said groove sloping downwardly from the mid-point in each direction longitudinally of the member, a fuse strip positioned in said groove, and means for retaining said strip initially in intimate surface contact with the bottom of said groove, said member being made of heat absorption material of predetermined mass relative to the amperage capacity of said strip, and said strip and member having different coefficients of thermal expansion whereby contact between a portion of the strip and the bottom of the groove is removed upon continued overload heating of the strip and member.

13. A replacement unit for cartridge type time lag fuses comprising an elongated substantially semicylindrical member of insulating material, said member having a groove in the flat surface thereof, a fuse strip positioned in said groove, and means for retaining said strip initially in intimate surface contact with the bottom of said groove, said member being made of heat absorption material of predetermined mass relative to the amperage capacity of said strip to absorb heat from and delay expansion of the strip for a predetermined period for a given overload through the strip, and said strip having a greater coefficient of thermal expansion than said member whereby a portion of the strip moves out of contact with the bottom of the groove upon continued overload heating of the strip.

LAMBERT SCHMIDT,
GEORGE SCHMIDT.
